[57] CLAIM

The ornamental design for an electronic drum, as shown and described.

DESCRIPTION

FIG. 1 is a front elevational view of an electronic drum showing our new design;

FIG. 2 is a side elevational view thereof;

FIG. 3 is a side elevational view of the side opposite that shown in FIG. 2;

FIG. 4 is a rear elevational view thereof;

FIG. 5 is a top plan view thereof; and,

FIG. 6 is a bottom plan view thereof.

Portions of the cord members have been shown in fragment in FIGS. 1 through 3 for ease of illustration and to indicate indeterminate length. Portions of the cord members and the drum stick members have been omitted from FIGS. 4 through 6 for ease of illustration.
